D. W. PAYNE

WARM AIR FURNACE

Filed May 29, 1922

Inventor:
Daniel W. Payne.
By Daniel Marklow,
his attorney.

UNITED STATES PATENT OFFICE.

DANIEL W. PAYNE, OF LOS ANGELES, CALIFORNIA, ASSIGNOR TO PAYNE FURNACE & SUPPLY CO., OF LOS ANGELES, CALIFORNIA, A CORPORATION OF CALIFORNIA.

WARM-AIR FURNACE.

Application filed May 29, 1922. Serial No. 564,486.

To all whom it may concern:

Be it known that I, DANIEL W. PAYNE, a citizen of the United States, residing at Los Angeles, in the county of Los Angeles, ⁵ State of California, have invented certain new and useful Improvements in Warm-Air Furnaces, of which the following is a specification.

This invention has to do with furnaces ¹⁰ for heating air for houses and the like; and it is a general object of the invention to provide a furnace of high heat efficiency. Among other and more particular objects ¹⁵ of the invention, it is an object to provide an arrangement and construction to prevent condensation of moisture taking place at any point within the furnace.

Further objects of the invention, and the features of accomplishment of the invention, ²⁰ will all be best understood from the following detailed description of a specific and preferred form of furnace which embodies the invention, reference for this purpose being had to the accompanying drawings, in which:—

Fig. 1 is a plan section taken as indicated by line 1—1 on Fig. 2; and Fig. 2 is a vertical section taken as indicated by line 2—2 on Fig. 1.

²⁵ An outer casing is shown at 10, this casing having side walls and a top and arranged to rest upon the floor. Within this outer casing there is a downwardly extending wall 11; and air entering the openings ³⁰ at 12 passes down between the outer casing and wall 11, to the lower edge of wall 11, and thence under that lower edge and up through and around the interior parts of the furnace.

³⁵ The heating burner of the furnace is shown at 15; located in the lower part of a combustion box 16, of configuration as shown in the drawings. The lower part of this box 16 is narrower in width than the upper part, and the burner is located substantially wholly in this narrower lower part. Horizontal shoulders are provided ⁴⁰ at 17 in the combustion box; and on the inner edges of these horizontal shoulders upwardly extending baffle walls 18 are erected, these baffle walls being composed of what is known as split fire bricks—fire-brick of about one inch thickness; and the upper edge of each baffle is covered with an

inverted channel 19, to hold the baffle in ⁴⁵ place.

Outside these baffles, and located just above the shoulders 17, are several outlets 20, leading to the lower ends of an equal number of vertical flues 21. These flues ⁵⁰ 21 are connected at their upper ends by horizontal pipes 22 with an outlet chamber 23, from which the draft flue or stack 24 finally carries away the gases of combustion.

Extending vertically through each one of ⁵⁵ the flues 21, there is an air tube 25, open at its bottom to entry of air, and open at its top to deliver air out into the upper part of the air casing 10. It will be noted that the air casing surrounds the interior structure in such a way as to leave an air space all around; so that air that enters the air casing, as before described, can pass all around the interior structure. Also it will be noted that the several flues 21 are spaced ⁷⁰ 75 apart and are spaced away from the combustion-box 16; so that air can pass all around the flues and can pass all around the combustion-box; and also around the pipes 22 and the outlet chamber 23. Consequently, as will be readily recognized, there is an easy and free flow of air upwardly ⁸⁰ through the whole interior space, all around the heated parts; and also of course through the air tubes 25. The heated air passes off ⁸⁵ through air pipes 30 which connect with the top of the air casing.

The coolest air is that at the bottoms of tubes 25, and around the bottoms of flues 21, and around the outlets 20. It is here ⁹⁰ that condensation of moisture in the gases of combustion is most likely to take place, if the gases of combustion are cooled below a certain point. Sudden cooling of the gases of combustion below a certain temperature causes deposition of moisture in ⁹⁵ the passages. I have provided against this, however, by delivering the gases, while they are at substantially their highest temperature, into the lowermost parts of flues 21; ¹⁰⁰ so that the gases that thus come into contact with the coolest air are comparatively hot, and are not cooled to the condensation point. Another feature is this: That the gases, as will be noted, once they are delivered to the flues 21, then move directly upwardly without any reverse downward movement such as would cause a trap to

hold condensation that would be deposited at the bottom of the downward movement. Thus, in my present arrangement, any condensation that tends to take place, is carried along with the upwardly moving streams of combustion gases, and carried out of the furnace without any opportunity of deposit.

Another feature of the furnace is this: 10 The combustion-box 16 is large enough to allow the gases of combustion to fully expand and therefore to come to a uniform high temperature. These gases of uniform high temperature then pass downwardly 15 outside of baffle walls 18 into the outlets, as before described. The baffle walls 18 thus provide for two things; in the first place they cause the gases of combustion to travel first to the upper part of combustion-box, with opportunity to acquire a uniform high temperature, and prevent combustion gases of extremely high temperature from going directly from the burner to the outlet 20; and they also shield the side walls 25 of the combustion-box, and the outlet 20, against the intense direct radiation effects from the burner. These baffle walls 18, being constructed of firebrick, also hold a considerable amount of heat, and thus again 30 tend to make the heating uniform. The heat of the gases of combustion, however, is not at all lost, as it is radiated to the baffle walls 18 and to the exterior walls of the combustion box, and all of this is of 35 course eventually radiated or conducted out into the surrounding upwardly moving stream of air. But the point I wish to make in this connection is this: That this heat is radiated at a uniform high temperature, 40 but not at an excessively high temperature; so that the air is heated uniformly, without any danger of being overheated or parched. Also the result of this arrangement is that the gases of combustion delivered into flues 21 are of a uniform high 45 temperature, but not of too high a temperature. Thus the result of all this arrangement, wherein the gases of combustion are uniformly heated, and wherein the air is 50 uniformly and freely distributed around and over all of the heating surfaces, is to uniformly and thoroughly warm the air to a proper temperature, without any danger of overheating or parching the air at any 55 point, and also without any opportunity for condensation deposit taking place at any point within the furnace.

Air for combustion in the combustion box is admitted at 35; the air thus admitted being air which has been somewhat 60 warmed by the time it reaches the opening. The burners may be controlled by the valve control means indicated at 36, outside the air casing.

Having described a preferred form of 65 my invention, I claim:

1. An air warming furnace that includes an outer air casing and an enclosed furnace structure, the furnace structure embodying a combustion box with heating 70 means therein, a chamber, surrounding the furnace structure, formed by inner walls extending downwardly from the top of the outer casing to adjacent its bottom and spaced from its vertical walls, the outer 75 casing having openings adjacent its top to feed air downwardly through the passage formed between it and the inner walls and beneath the bottom edges of said walls, a plurality of vertical combustion flues extending upwardly from the lower part of the combustion box, intermediate said box and the inner walls, and connecting at the top with an outlet, each of said flues having an air passage extending longitudinally 80 through its vertical portion.

2. An air warming furnace that includes an outer air casing and an enclosed furnace structure, the furnace structure embodying a combustion box with heating means therein, an inner chamber, surrounding the furnace structure, formed by inner walls extending downwardly from the top of the outer casing to adjacent its bottom and spaced from its vertical walls to form air 90 passages therebetween, openings in the outer casing adjacent its top to admit air to said passages, a plurality of vertical combustion flues extending upwardly from the sides of the combustion box, from points 95 adjacent its bottom, and connecting at the top with a common outlet, said flues extending between the combustion box and said inner walls, each of said flues having an air passage extending longitudinally 100 through its vertical portion, from points adjacent the bottom edges of the inner walls to points spaced from the top of the outer casing, and warm air openings extending 105 from the top of the inner chamber.

In witness that I claim the foregoing I have hereunto subscribed my name this 5th day of May, 1922.

DANIEL W. PAYNE.
